TOOTHBRUSH

Filed July 29, 1929

Inventor

RALPH G. HAWKSLEY.

By *Clarence A. O'Brien*, Attorney

UNITED STATES PATENT OFFICE

RALPH GOODWIN HAWKSLEY, OF AUBURN, RHODE ISLAND

TOOTHBRAHSH

Application filed July 29, 1929. Serial No. 381,963.

This invention relates to improvements in tooth brushes.

The primary object of the invention resides in a tooth brush in which the handle 5 constitutes a holder for a tube of dentifrice, and means whereby the contents of the tube may be dispensed directly upon the bristles of the brush in such quantities and at such time as is required.

10 Another object of the invention is to provide a combined tooth brush and dentifrice holder embodying a flexible tube connected to the outlet end of the dentifrice tube and normally held in an out of the way position 15 so as not to interfere with the use of the brush during the brushing of the teeth, but which flexible tube may be moved to a position over the bristles of the brush to deposit a quantity of dentifrice thereon.

20 A further object resides in a tooth brush in which the tube of dentifrice is removably connected thereto, and which permits replacement of a dentifrice tube as the same is emptied of its contents.

25 With these and other objects in view, the invention resides in certain novel construction and combination and arrangement of parts, the essential features of which are hereinafter fully described, are particularly 30 pointed out in the appended claims, and are illustrated in the accompanying drawings, in which:

Figure 1 is a perspective view of my improved tooth brush showing the sanitary 35 cover in position over the bristles of the brush.

Figure 2 is a vertical longitudinal view through the tooth brush showing the sanitary covering in dotted lines, the flexible 40 discharge tube in operative position in full lines, and in an inoperative position in dotted lines.

Figure 3 is a vertical transverse sectional view on the line 3—3 of Figure 2.

45 Figure 4 is a vertical longitudinal section-

al view through a modified form of my invention.

Referring more particularly to the drawing, the reference numeral 10 designates my improved tooth brush in its entirety, which 50 includes a hollow handle member 11 open at one end and which is provided with an inwardly extending threaded nipple 12 at its opposite end. The open end of the handle member is provided with the hinged door 13 55 whereby a tube of dentifrice or the like 14 may be inserted and the door 13 swung to a closed position to retain the same therein. The threaded neck or discharge end of the dentifrice tube 14 threadedly connects with 60 the nipple 12 as clearly shown in Figure 2 of the drawing. The head 15 is contiguous from one wall of the casing or hollow handle 11 and contains the usual bristles 16. For the purpose of maintaining the bristles in a 65 sanitary condition when the brush is not in use, I provide a cover member 17, which is open at one end for the insertion of the cover over the bristles end of the brush, and which open end is provided with a hinged 70 door 18 provided with a cut out portion 19 to accommodate the extending shank between the head and the casing 11.

The construction herein before described is generic to the two forms of my invention 75 shown in Figures 1 to 3, inclusive, and Figure 4, but in the preferred form shown in the first three figures I employ a novel means by which the contents of the collapsible tube 14 may be dispensed.

In this form I provide a plurality or series 80 of push buttons 20, each of which includes an outer manipulating head 21 and an inner presser head 22, the said head being connected by a shank 23 slidably mounted in one of the side walls of the casing or handle member 11. When a full tube of dentifrice is inserted into the hollow handle, all of the push buttons 20 will be in an outwardly extended 85 position, and in use, the outer end push but- 90

ton is first manipulated to compress the base or lower end of the collapsible tube, and when fully compressed, the operator proceeds to depress the next adjacent push button. It will be seen that when all of the push buttons are in a fully depressed position, the full contents of the collapsible tube will be dispensed.

Connected to the nipple 12 is an elastic flexible tube 24, of a length sufficient to extend to a position over the bristles of the brush, whereby dentifrice compressed from the tube 14 may be deposited upon the bristles of the brush for use. When not in use, the said flexible tube 24 may be bent backward and held in an inoperative position by the insertion of the same into a spring clip 25 mounted on the hollow handle 11 as clearly shown in dotted lines in Figure 2 of the drawing. This same flexible tube is shown in the modified form in Figure 4 of the drawing and like reference characters refer to like parts therein.

In Figure 4 the hollow handle 11 is provided with a longitudinal slot 26 in which a manipulating member or carriage 27 is slidably mounted, the said member 27 having a roller 28 journaled therein and disposed within the said casing to ride over the collapsible tube 14.

From the foregoing it will be understood that upon manual movement of the manipulating member 27, longitudinally of the hollow handle 11, the roller 28 will tend to flatten out the collapsible tube 14, whereby the full contents of the said tube may be dispensed.

While I have described what I deem to be the most desirable embodiment of my invention, it is obvious that many of the details may be varied without in any way departing from the spirit of my invention, and I therefore do not limit myself to the exact details of construction herein set forth to anything less than the whole of my invention limited only by the appended claims.

Having thus described the invention, what I claim as new and desire to secure by Letters Patent is:—

50 1. A tooth brush having a hollow handle, a door at one end thereof, a collapsible tube housed within said hollow handle, a flexible tube connected to the discharge end of said collapsible tube, the free end of said flexible tube adapted to be manually positioned over the bristles of said brush, means on said handle for securing said flexible tube in a flexed inoperative position away from the bristles of the brush, and means on said handle engageable with said collapsible tube for squeezing the contents thereof out through said flexible tube.

60 2. A tooth brush having a hollow handle, a door at one end thereof, a collapsible tube housed within said hollow handle, a flexible

tube connected to the discharge end of said collapsible tube, the free end of said flexible tube adapted to be manually positioned over the bristles of said brush, and means on said handle engageable with said collapsible tube for squeezing the contents thereof out through said flexible tube, said means including a series of push buttons slidably mounted in said handle and successively operable for pressing engagement with said collapsible tube.

In testimony whereof I affix my signature.
RALPH GOODWIN HAWKSLEY.
